UNITED STATES PATENT OFFICE.

HERBERT O. BROWN AND JOHN R. DONNELLY, OF FAIRFIELD, MAINE.

SAD-IRON.

SPECIFICATION forming part of Letters Patent No. 656,088, dated August 14, 1900.

Application filed April 12, 1899. Serial No. 712,719. (No model.)

To all whom it may concern:

Be it known that we, HERBERT O. BROWN and JOHN R. DONNELLY, citizens of the United States of America, and residents of Fairfield, 5 Somerset county, State of Maine, have invented certain new and useful Improvements in Sad-Irons, of which the following is a specification.

Our invention relates to gas-burning sad- 10 irons, and particularly to those adapted to burn gasolene gas, the perfect combustion of which is difficult. Such irons are made hollow and they have resting on the bottom elongated, perforated, and open-bottomed 15 burners, which serve simply to mingle the gas and air on the principle of the Bunsen burner, discharging it into the inside of the hollow iron through small perforations, the actual combustion taking place in the body of the 20 iron after leaving the burner.

Our invention is directed to the improved construction of sad-irons in the direction of producing the most perfect combustion and of transferring the greatest quantity of heat 25 to the bottom of the iron; and it consists in the arrangement and combination of parts, as hereinafter described and claimed.

The invention is illustrated by means of the accompanying drawings, in which—

30 Figure 1 is a vertical longitudinal section through the center of the iron, and Fig. 2 is a cross-section on the line $x-x$ of Fig. 1.

A represents the body of the sad-iron, and it is made hollow and in two parts, these 35 parts being held together by means of bolts h and having interposed between them an asbestos diaphragm a . This diaphragm divides the interior of the iron into two unequal chambers, the lower or heating chamber having perforations b at the top and j at the bottom to insure the circulation of gas. The diaphragm a and the air-space above it prevent the heat from getting into the top of the iron and confine it at the bottom when 45 it is needed.

Resting on the bottom B , which is preferably of copper, is the elongated combustion-chamber E , which extends nearly the entire length of the iron. The combustion-chamber 50 E is preferably in the form of a semicylinder with an open-bottom, and it is supported on the bottom by means of supporting cross-bars g , the ends of which turn up and thus secure

them in place on the combustion-chamber. These cross-bars, being in the line of the 55 flame and having a considerable surface in contact with the bottom, readily absorb the heat of the flame and transfer it to the bottom. Gas is introduced into the chamber through the pipe i , which passes down through the handle-support c , through the top of the combustion-chamber, and connects at its lower end with the T connection or spreader h , by which the current of gas is divided and directed horizontally toward each end of the 60 combustion-chamber. This T connection prevents the gas from impinging directly on the bottom of the iron and insures an even distribution and combustion.

The escape of the burning gas from the 65 combustion-chamber is provided for by openings f at the top, while the spaces between the cross-bars g allow the air to come in at the bottom. In order to prevent the escape of unconsumed gas at the ends of the combustion-chamber, we stop the ends with plugs e , made of asbestos or other refractory material, and a lining o of the same material is provided for the combustion-chamber.

The handle d of the sad-iron is connected 70 with the handle-support c .

In the operation of our sad-iron the gas and air mixed together is introduced through the pipe i , and, dividing in the spreader, it is thrown toward each end of the combustion-chamber in a horizontal direction. The ends 75 e and the lining o soon become incandescent and the gas is thoroughly burned.

We claim—

The herein-described gas-burning sad-iron 80 provided with an open-bottomed, elongated perforated combustion-chamber in which the combustion takes place having refractory end walls, conduction-supports beneath the combustion-chamber for raising the same above 85 the bottom of the iron and conducting heat to the bottom, and a gas-pipe for supplying gas to said combustion-chamber, substantially as described.

Signed by us at Fairfield, Maine, this 11th 90 day of March, 1899.

HERBERT O. BROWN.
JOHN R. DONNELLY.
